TOOTHBRUSH HOLDER

Gordon R. Cedarleaf, Rockford, Ill., assignor to
Gust E. Lindstrom, Rockford, Ill.

Application January 31, 1947, Serial No. 725,577

1 Claim. (Cl. 211—66)

1

This invention relates to tooth brush holders and more particularly to a holder of the type adapted to support a plurality of tooth brushes.

A primary object of the invention is to provide an improved holder of the above character which is simple and sturdy in construction, which is rugged and which is relatively inexpensive to manufacture.

Another object of the invention is to provide a holder of the above character that is adapted to efficiently utilize waste space under a small shelf, such as a glass shelf secured to a wall in a bathroom adjacent a wash basin.

A still further object of the invention is to provide a tooth brush holder of the above character which can be quickly and conveniently clamped to shelves of different thicknesses and which supports tooth brushes so that neither the holder nor the supported tooth brushes obstruct or interfere with the accessibility of the respective shelf.

Yet another object of the invention is to provide a tooth brush holder of the above character that can be readily and easily cleaned so that it can be maintained in a sanitary condition.

Other objects and advantages of the invention will become apparent from the following detailed description taken in connection with the accompanying drawings, in which—

Figure 1 is a perspective view of a tooth brush holder embodying the present invention.

Fig. 2 shows a stamping from which the holder is formed.

Fig. 3 is a side view of the holder shown in Figure 1.

Fig. 4 is a view taken along the line 4—4 of Fig. 5.

Fig. 5 is a view showing the holder in a clamped position with respect to a relatively thin shelf.

Fig. 6 is a view showing the holder in a clamped position with respect to a thicker shelf than shown in Fig. 5.

Fig. 7 is a view showing the holder in a clamped position with respect to a glass shelf having a beaded forward edge.

Fig. 8 is a perspective view showing the holder in a clamped position and supporting a plurality of brushes.

Referring now to the drawings the invention is shown embodied in a tooth brush holder formed from a single piece of flat metal comprising a body 10 secured to a shelf 11 and having a plurality of hooks 12 arranged for suspending tooth brushes 13. In the past, tooth brush holders that have been constructed to be clamped on the shelf

2

11 have been of a type that suspends the brushes 13 from the forward edge of the shelf 11 or supports the brushes so that the heads of the brushes and the bristles extend up past the edge of the shelf. Thus, it is apparent that tooth brushes held in this manner are subject to being accidentally dropped to the floor which, of course, is unsanitary, or in the case where the head and bristles extend up past the forward edge of the shelf, the head and bristles form an obstruction that interferes with the accessibility of the shelf. Accordingly, my invention is concerned with providing a holder that is adapted to be supported by the shelf 11 and arranged so as to support the brushes 13 so as not to interfere with the accessibility of the contents, such as bottles, lotion jars, and similar items, usually found on the shelf 11 of this character. Thus, it contemplates a holder having hooks 12 arranged so that the tooth brushes 13 are suspended beneath the shelf 11 and rearwardly of the forward edge, thereof. In the present instance the hooks 12 are formed by generally L-shaped members 19, comprising a stem portion and a toe portion, integral with and depending from the edges of body 10. As shown in Figs. 3 and 5 the toes 20 of the L-shaped members are fashioned so as to be inclined slightly upwardly toward the body 10 such that the tooth brushes 13 must be raised bodily before they can be removed from the hooks 12. This construction prevents accidental displacement of the tooth brushes 13. The hooks 12 open toward the forward edge of the shelf 11 thereby positioning the toes 20 of the hooks 12 so that the toes 20 can be conveniently inserted in the holes formed in the handles of the tooth brushes 13.

In the present embodiment of the invention the body 10 is shaped to form a clamping member having self-adjusting jaws 21 and 22 arranged to secure the holder to the shelf 11 such that the suspending hooks 12 are on the underside thereof. As shown in Fig. 5 the jaw 21 is formed by a bottom portion 23 of the body and the jaw 22 is formed by an elongated arm 24 overlying the bottom 23. At one end the bottom 23 and the arm 24 are held in a spaced relation by a front 25 integral with both the bottom 23 and the arm 24. At the opposite end (see Fig. 3), the bottom 23 and arm 24 converge toward each other. The bottom and the arm are formed from resilient material so that when the jaws 21 and 22 engage opposite sides of the shelf 11 the holder is automatically secured in position. It is apparent with this clamp construction that the

jaws are self-adjusting so that the holder can be quickly and readily secured to shelves of different thicknesses and construction of the forward edge of the shelf 11 such as shown in Figs. 5, 6, and 7.

A low cost device is produced because the holder can be readily formed from a single piece of relatively thin flat metal. Thus, the original stamping takes the shape shown in Fig. 2. It will be observed that the L-shaped members 19 are spaced alternately along opposite sides of the stamping. In this manner, the L-shaped members of an adjacent stamping are formed between the L-shaped members of the first stamping so as to minimize waste material inherent in a stamping process. To form the holder, it is a simple matter of bending the L-shaped members 19 in one direction at substantially right angles relative to the body of the stamping and then bending the body in the opposite direction to form the front 25, and then reversely on itself as shown in Fig. 3.

It is obvious that the dimensions of the front 25 may be varied in accordance with the thickness of the shelf 11 with which the holder is going to be used. Inasmuch as only the simplest forming operations are utilized, it will be observed that this construction provides a tooth brush holder that can be readily and easily cleaned and washed since there are no small cracks or crevices formed in the shaping of the holder and all the surfaces are smooth.

To install the holder it is only necessary to spread the jaws 21 and 22 a sufficient distance so that they slip over the forward edge of the shelf 11. The holder is then pushed bodily rearwardly with respect to the forward edge of the shelf until the edge of the shelf engages the front 25.

It is apparent that this construction provides a tooth brush holder that can be quickly and easily installed and that is simple and inexpensive to make. It also forms a holder for tooth brushes that is positioned beneath a shelf there-

by utilizing space that is normally not used and also provides a tooth brush holder that supports brushes so that neither the holder nor the brushes obstruct or interfere with the accessibility of the shelf.

I claim:

A tooth brush holder adapted to be mounted on the forward edge of a shelf, comprising a single elongated piece of sheet metal stamped to provide a body portion and tooth brush suspension hooks spaced alternately in staggered relation along the extreme opposite sides of the body, said body being bent back upon itself to form spaced upper and lower elongated narrow portions shaped to extend rearwardly from the forward edge of the shelf a substantial distance to engage the top and bottom surfaces thereof and forming shelf gripping jaws, each said hook being bent to depend from the extreme sides of the lower portion and being formed with a forwardly extending upwardly inclined toe portion, said hooks at each side being spaced apart along that side and said body being sufficiently wide to space apart the hooks at the respective sides to permit simultaneous suspension of a tooth brush on each of said hooks.
